US00D926964S

(12) **United States Design Patent** (10) **Patent No.:** **US D926,964 S**
(45) **Date of Patent:** **** Aug. 3, 2021**

(54) **DIETARY SUPPLEMENT**

(71) Applicant: **Nutramax Laboratories, Inc.**,
Lancaster, SC (US)
(72) Inventors: **Brian Adams**, Lancaster, SC (US);
David Griffin, Forest Hill, MD (US);
Hubert Ratkowski, Simpsonville, SC
(US)

(73) Assignee: **Nutramax Laboratories, Inc.**,
Lancaster, SC (US)

(**) Term: **15 Years**

(21) Appl. No.: **29/730,685**

(22) Filed: **Apr. 7, 2020**

(51) LOC (13) Cl. **28-01**

(52) U.S. Cl.
USPC **24/103; D1/127**
